(57) **CLAIM**

The ornamental design for a fully enclosed fused filament fabrication 3D printer, as shown and described.

DESCRIPTION

FIG. 1 is a perspective view of a fully enclosed fused filament fabrication 3D printer showing the new design.

FIG. 2 is another perspective view of the fully enclosed fused filament fabrication 3D printer of FIG. 1.

FIG. 3 is a further perspective view of the fully enclosed fused filament fabrication 3D printer of FIG. 1.

FIG. 4 is a front view of the fully enclosed fused filament fabrication 3D printer of FIG. 1.

FIG. 5 is a rear view of the fully enclosed fused filament fabrication 3D printer of FIG. 1.

FIG. 6 is a side view of the fully enclosed fused filament fabrication 3D printer of FIG. 1.

FIG. 7 is an opposite side view the fully enclosed fused filament fabrication 3D printer of FIG. 1; and,

FIG. 8 is a top view the fully enclosed fused filament fabrication 3D printer of FIG. 1.
